(57) **CLAIM**

The ornamental design for a flying insect trap, as shown and described.

DESCRIPTION

FIG. 1 is a front, top perspective view of a flying insect trap, showing my new design;

FIG. 2 is a rear, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 2;

FIG. 10 is a partial enlarged view of FIG. 3; and,

FIG. 11 is a partial enlarged view of FIG. 8.

The dashed broken lines in the figures are for the purposes of illustrating portions of the flying insect trap that form no part of the claimed design.

The short-short-long dashed broken lines immediately adjacent to the claimed areas in the figures represent the boundaries of the design and form no part of the claimed design. The dash-dot-dash broken lines are for notating enlarged views and form no part of the claimed design.
